CARBURETOR STRUCTURE

Irven E. Coffey, Normandy, Mo., assignor to
 Carter Carburetor Corporation, St. Louis, Mo.,
 a corporation of Delaware

Application July 25, 1940, Serial No. 347,415

7 Claims. (Cl. 261—39)

This invention relates to carburetors for internal combustion engines and consists particularly in novel means incorporated in an automatic choke carburetor for indicating to the operator the point in the throttle opening movement when the usual throttle operated "unloader" mechanism is about to become effective to open the choke valve.

During cold starting of an automobile engine, the choke valve is normally closed and the throttle valve partly open. In case the engine should become "loaded" due to the drawing of excessive gasoline into the cylinders, it is necessary to open the choke valve and turn over the engine a few times in order that this excessive fuel may be swept out of the cylinders. This "unloading" is usually affected through a connection to the throttle valve which positively opens the choke valve when the throttle is substantially fully opened.

There has been a tendency to provide for energizing the usual engine self-starter motor by partial movement of the throttle pedal, instead of through the intermediary of a separate pedal or button. Where such "unloader" and starting functions are controlled by the throttle pedal, the driver may inadvertently depress the pedal far enough during cranking, to force the choke valve open, wherefor it may be impossible to get started.

Accordingly, the main object of the present invention is to provide means to indicate to the driver a point in the throttle opening movement just prior to that at which the "unloader" mechanism is rendered effective to open the choke valve.

A more detailed object is to provide mechanism operated jointly by the choke valve when closed and the throttle valve when substantially open to apply sensible resistance to further opening of the throttle valve.

Another object is to provide means for rendering such additional indicating resistance ineffective upon still further opening movement of the throttle so that the driver need not oppose such resistance while cranking the engine with the choke in the "unloading" position.

Still another object is to provide means for freeing the choke valve from the indicating mechanism when the throttle has been moved to its proper starting position so as to facilitate pulsations or "breathing" of the choke valve during cranking.

These objects and other more detailed objects

are attained substantially by the structure illustrated in the accompanying drawing in which:

Fig. 1 is an elevation of an automobile carburetor showing the invention applied thereto, parts being sectioned for clearer illustration.

Fig. 2 is an elevational view showing certain parts of the structure in Fig. 1, but with the choke valve closed.

Fig. 3 is a view similar to Fig. 2 but showing the choke valve closed and the throttle valve partly opened to its starting position, and

Fig. 4 is a view similar to Figs. 2 and 3 but showing the throttle valve fully opened and the choke valve in its "unloaded" position.

15 The carburetor shown in Fig. 1 includes a barrel 1 forming a downdraft mixture conduit and pivotally mounting an unbalanced choke valve 2 having a shaft 3, journaled in the upper portion of the mixture conduit, and a butterfly 20 throttle valve 4 secured to a shaft 5 journaled in the lower part of the mixture conduit. At one side of the mixture conduit, choke shaft 3 extends into automatic choke control housing 6 which contains thermostatic mechanism for 25 yieldingly closing the choke valve under cold starting conditions. Suitable automatic choke mechanism is fully described and claimed in Patent No. 2,085,351 issued to the present inventor.

30 Projecting from the lower part of the mixture conduit adjacent throttle valve 4 is an inclined housing 7 slidably receiving an outer plunger 8 and an inner plunger 9 telescopingly received in plunger 8. Inner plunger 9 has a projecting 35 stem 10 to which is secured a switch contacting plate 11 for cooperating with terminal screws 12 to close a circuit for controlling the usual self-starter motor (not shown). Outer plunger 8 cooperates with throttle shaft 5 in such a manner 40 that when the throttle valve is opened to its normal starting position, substantially as in Fig. 3, contact plate 11 engages screws 12 to energize the starter circuit. This starter switch mechanism is disclosed and claimed in detail in a Patent No. 2,174,313 issued to the present inventor.

45 Formed rigidly on choke shaft 3 is a plate 15 and loosely mounted on shaft 3 inside this plate is an eccentric cam element 16. A pintle 17 adjacent choke shaft 3 loosely mounts a bell crank 50 18 carrying a screw 19 in one arm thereof for cooperating with cam 16, and having a laterally projecting headed pin 20 at the extremity of its other arm. A link 21 has a slot 22 in its upper portion which slidably receives pin 20 and, at its lower portion, is pinned at 23 to a crank 24 rigid

with throttle shaft 5. The interconnection mechanism as thus described is arranged so that when the choke valve is in closed position, the closing movement of the throttle valve is limited by engagement of screw 19 with a relatively high point 26 on cam 16, as in Fig. 2, this being known as a "fast idle" position. Thereafter, as the choke valve opens, cam 16 is swung counterclockwise toward the position shown in Fig. 1 in which a recessed portion 27 of the cam is opposite screw 19 and the throttle valve is permitted to close to its normal idling position.

In addition, means is provided for positively opening the choke by substantially full opening movement of the throttle valve, as indicated in Fig. 4. This means comprises an inwardly projecting lip 28, on the upper portion of link 21, which is positioned to engage a projecting portion 29 on plate 15 to rotate the choke valve in the opening direction. By reference to Figs. 3 and 4, it will be seen that the throttle valve, in its unloading position, as in Fig. 4, is substantially farther opened than is this valve in its starting position, as in Fig. 3. The difficulty is that the operator may not be able to distinguish, in the operation of the throttle pedal, between the two throttle positions shown in these views.

In order to provide a positive indication that the throttle valve is opened sufficiently to energize the starter circuit and that upon further movement the choke valve will be opened, the following mechanism is provided: Loosely pivoted on pintle 17 outside of bell crank 18 is a weighted lever element 31 which is normally maintained in the inoperative position, as in Fig. 1, due to its eccentrically weighted lower portion. Element 31 has a finger 32 projecting upwardly therefrom, the finger having an inclined upper edge 33 positioned to be engaged by an outward lug 34 on choke plate 15, when the choke is closed, to rotate element 31 slightly in a clockwise direction or, in other words, to its operative position. Pivotaly mounted on interconnection link 21, intermediate the ends thereof, is a trigger finger device 35 which is constantly urged in a counterclockwise direction by a spring 36 encircling the finger and link 21. This finger has an inclined upper edge 37 which is disposed to engage an outwardly projecting pin 38 at the lower extremity of element 31, when this element is moved to its operative position, as in Fig. 2, in the path of finger 35, and the throttle valve is opened substantially to its starting position, as in Fig. 3. Upon slight additional opening movement of the throttle, edge 37 on finger 35 operates by cam effect upon pin 38 to rotate element 31 slightly in a clockwise direction (Fig. 3) and free plate 15 and the choke valve from finger 32. Thus, in the starting position of the choke and throttle valves, the choke valve movement is desirably restricted solely by the automatic choke mechanism.

When pin 38 is lodged between inclined edge 37 on finger 35 and the adjacent edge of link 21, as in Fig. 3, further opening movement of the throttle is sensibly resisted by spring 36 through finger 35, pin 38, and element 31. Continued opening movement of the throttle valve, against this resistance, causes finger 35 to be forced clockwise through camming action against pin 38 and ultimately, inclined edge 37 on the finger will clear pin 38 and inner edge 39 of the finger will engage the pin, whereupon the mechanical advantage acting against spring 75

36 will be greatly increased due to the sharp angular change in the inclined plane or camming action. This snap-over action occurs just prior to engagement of choke plate projection 5 29 by lip 28, as indicated by the broken line position of elements 28 and 35 in Fig. 3. After the snap-over action the parts 35, 36 and 38 no longer apply sensible resistance to further opening of the throttle and the actual opening of 10 the choke for unloading purposes is effected, after the momentary indication thus afforded, by substantially normal pedal pressure.

Accordingly, it will be seen that I have provided effective means for momentarily indicating to the operator that the throttle valve is opened far enough for energizing the starter circuit, but without opening the choke, and further, the mechanism does not effect the choke valve during the cranking operation nor does it 20 effect throttle opening movement under normal running conditions when the choke valve is fully opened.

The invention may be modified in various respects as will occur to those skilled in the art 25 and the exclusive use of all such modifications as come within the scope of the appended claims is contemplated.

I claim:

1. In a carburetor, choke and throttle valves, 30 yielding means to close said choke valve for starting, means operated by an opening movement of said throttle beyond a predetermined position to open said choke valve against said yielding means, resilient means connected to 35 said throttle and operatively independent of said choke valve, and a movable abutment arranged to be moved to a position by the closing of said choke valve to cooperate with said resilient member to resist the opening of said throttle 40 prior to said predetermined position, said resilient member being movable with relation to said abutment after contact therewith by a further movement of said throttle valve beyond said predetermined position whereby the resistance to throttle opening movement is decreased.

2. In a carburetor having a body member, choke and throttle valves, a shaft for said choke valve, yielding means to close said choke valve for cold starting, an arm fixed to said shaft, a shiftable abutment mounted on said body member, means movable with said choke valve for shifting said abutment into operative position, mechanism connected to said throttle and having a part adapted to contact said arm as said throttle 50 is moved outward a predetermined degree whereafter further opening movement of said throttle will cause an opening of said choke valve, said mechanism including a spring pressed element movable therewith having a steep cam surface arranged to contact said abutment as said throttle valve is moved outward and before said predetermined degree has been reached to provide an indicating resistance to throttle opening, said steep cam surface being movable against spring tension out of contact with said abutment by continued opening movement of said throttle.

3. In a carburetor having a body member, choke and throttle valves, yielding means to close said choke valve for starting, means connected to and operated by an opening movement of said throttle for opening said choke valve against said yielding means, mechanism for indicating starting position of said throttle including a shiftable abutment mounted on said body member, resil-

ient means connected to said throttle and operatively independent of said choke valve and arranged to cooperate with said abutment when said throttle valve is opened beyond starting position to resist such opening movement, said resilient means being arranged to offer substantially reduced resistance when said throttle valve is opened beyond starting position and means movable with said choke valve for shifting said abutment into operative position as said choke valve is moved to a closed position.

4. In a carburetor, choke and throttle valves, yielding means to close said choke valve for starting, means operated by opening movement of said throttle to open said choke valve against said yielding means, mechanism for indicating starting position of said throttle including an element movable to an operative position by closing of said choke valve, and a resilient device connected with said throttle valve and operable independent of said choke valve for engaging said element as said throttle is moved openward to starting position to yieldingly resist said throttle opening movement, said resilient device being movable with respect to said movable element by continued throttle opening movement beyond starting position to a position whereby the resistance to throttle opening is abruptly and sensibly decreased.

5. In a carburetor, choke and throttle valves, yielding means to close said choke valve for starting, means operable by opening movement of said throttle valve beyond a predetermined starting position for opening said choke valve against said yielding means, mechanism for indicating starting position of said throttle including a movable abutment arranged to be moved to an operative position by closing of said choke valve, and a spring pressed snap-over device connected to said throttle and independent of said choke valve and arranged to contact said abutment upon opening movement of said throttle valve beyond said po-

sition to momentarily resist such throttle opening movement, and arranged to be rendered less effective by farther opening movement of said throttle valve beyond said position.

6. In a carburetor having a body member, a choke and throttle valve, yielding means for closing the choke for starting, means connected to and operated by an opening movement of the throttle valve beyond normal starting position to open said choke valve against said yielding means, mechanism for indicating starting position of said throttle including a spring pressed snap-over device connected with said throttle valve and a depending element carried by said body member, said depending device being positioned by movement of said choke to starting position for engagement with said snap-over device to momentarily yieldingly resist the throttle opening movement and means for rendering the throttle resistance less effective, said last named means being operated by a continued throttle movement.

7. In a carburetor, choke and throttle valves, yielding means to close said choke valve for starting, means operated by opening movement of said throttle to open said choke valve against said yielding means, mechanism for indicating the starting position of said throttle including an element movable to an operative position by closing of said choke, and a spring pressed pivoted member connected with said throttle and operable independent of said choke, said pivoted member including an inclined face for engaging said movable element as said throttle is moved openward to starting position to yieldingly resist said throttle opening movement, said pivoted member being movable with respect to said movable member by continued throttle opening movement beyond starting position to a position whereby the resistance to throttle opening is abruptly and sensibly decreased.
